UNITED STATES PATENT OFFICE.

GEORGE CODY, OF NEW YORK, N. Y.

DESIGN FOR A PLUMBER'S TRAP.

42,315.

Specification for Design.

Patented Mar. 19, 1912.

Application filed November 24, 1911. Serial No. 662,246. Term of patent 14 years.

To all whom it may concern:

Be it known that I, GEORGE CODY, a citizen of the United States of America, residing at New York city, borough of Brooklyn, county of Kings, State of New York, have invented a new, original, and ornamental Design for Plumbers' Traps, of which the following is a specification, reference being had to the accompanying drawing, forming part thereof, in which—

Figure 1 is a side view of the trap em-

bodying my design. Fig. 2 is a front view looking from the right of Fig. 1, and Fig. 3 is a back view looking from the left of Fig. 1.

I claim:

The ornamental design for a plumber's trap, substantially as shown.

GEORGE CODY.
